BOGIE COUPLER

Henry Handler, Aberdeen, Md.

Application April 2, 1945, Serial No. 586,257

6 Claims. (Cl. 280—80)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to movement of bogies of artillery mounts from given areas, as from the vicinity of the mount or from the field of fire after the bogies have been removed from the mount and the gun has been set up in position for firing. As is well known these bogies support the mount and provide the mobility for the artillery piece when it is in condition for traveling, but when the gun is set up for firing these wheeled bogies are removed so that the gun may be set on a firmer, more rugged foundation. After the bogies have been removed from the mount it is important that they be protected from damage by shell fragments, and the like, as otherwise the mobility of the mount may be seriously impaired or even destroyed, depending upon the extent of the damage inflicted on the bogies by opposing fire.

An important object of this invention is to provide for facilitating the removal of bogies from the field of fire, for example, to a region affording more protection, as to a rear area.

Another object is to provide for coupling the bogies together preferably so that they may have the maneuverability of a vehicle chassis having a front pair of wheels which may be swung around as desired to turn or guide the coupled bogies.

Another object is to provide a coupler which may be readily secured to the front and rear bogies of a gun mount so that the front bogie may be swung transversely to steer the coupled bogies as they are drawn away.

Another object is to provide a coupler adapted to take torsional strains without requiring a universal joint.

A further object is to provide a bogie coupler having an improved construction and relative arrangement of parts.

The features of the invention are illustrated in the accompanying drawing, wherein:

Fig. 1 is a perspective view, with parts omitted and broken away for purposes of illustration, and showing a bogie coupler connected to the front and rear bogies of a gun mount;

Fig. 2 is a perspective view of the rear bogie shown in Fig. 1, parts being omitted and broken away for purposes of illustration;

Fig. 3 is a perspective view of the front bogie

2

shown in Fig. 1 with parts omitted and broken away, and

Fig. 4 is a perspective view of the bogie coupler shown in Fig. 1.

In the drawings, a bogie coupler in accordance with this invention is indicated generally at 10 in Fig. 4. As shown in Fig. 1 this coupler is adapted to connect the rear bogie, indicated generally at 11 in Fig. 2, to the front bogie, indicated generally at 12 in Fig. 3.

The front bogie (Figs. 1 and 3) comprises a stationary axle 14 from which a central draft member 16 and right and left diagonal draft members 17 and 18, respectively, may extend to a lunette 19. At each end of the axle a suitable supporting wheel 21 may be mounted in any well known manner. A draft or pivot pin 22 (Fig. 1) is adapted to extend through upper and lower aligned openings or holes 23 between which there is a rearwardly opening recess 24 into which a member on the gun mount (not shown) is adapted to extend for pivotally connecting the gun mount to the front bogie by means of pivot pin 22.

The rear bogie 11 (Figs. 1 and 2) may comprise a stationary axle 26 which may have a substantially flat upper side 27 adapted to be substantially parallel with the ground when the bogie is in traveling position. A pair of bearing blocks 28

30 may be spaced along the right side of the axle, as viewed in Figs. 1 and 2, this being the rear side of the axle when the bogie is under the mount. These bearing blocks present inclined bearing surfaces 29 for cooperative engagement with portions of the mount (not shown). Beneath these bearing blocks, brackets 31 carried by the axle support swing bolts 32 equipped with manually operable tightening and locking nuts 33 for securing the swing bolts to the mount. From this same

40 side of the axle a pair of brackets 34 (Fig. 1) extend outwardly and curve upwardly for supporting a maneuvering bar 36. A pair of bearing blocks 37 similarly spaced along the opposite side of the axle present upwardly facing bearing surfaces 38 substantially co-planar with the upper flat side 27 of the axle, while on their under sides these bearing blocks present inclined bearing surfaces as indicated at 39. At each end of the axle

45 a suitable supporting wheel 41 may be mounted in any well known manner.

As shown in Fig. 4, the coupler 10 may be in the form of a substantially Y shaped frame comprising a longitudinal member 42 from which 55 diagonal members or arms 43 and 44 diverge.

Adjacent its forward end, longitudinal member 42 may have a substantially vertical bore 46 providing a pivot bearing for draft or pivot pin 22 carried by the front bogie.

For securing the coupler to the rear bogie, each of the divergent arms 43, 44 may be provided at its outer end with means for effecting cooperative interlocking engagement, preferably with complementary and interfitting parts of the bogie, as with the bogie axle, its bearing blocks, and the swing bolts thereof. For effecting cooperative engagement with the bogie axle and its bearing blocks, each of divergent arms 43, 44 may be equipped, preferably at its outer end, with a base plate or block 47 having its under side formed to provide a downwardly facing substantially flat surface, indicated at 48, adapted to span the flat upper surface 27 of the axle and co-planar bearing surface 38 and to ride upon these surfaces. Preferably, each base plate 47 is also provided with surfaces substantially complementary to the lateral surfaces of the bearing blocks, as with similarly inclined, substantially opposed bearing surfaces, indicated at 49 and 51, for engagement, respectively, with inclined bearing surfaces 39 and 29 of the bearing blocks.

In order that the swing bolts may be utilized for assisting in holding the coupler to the axle of the rear bogie, each of divergent arms 43, 44 may be finished with a suitable bifurcated or claw-like member 52, or 52', having a notch 53 to receive the shank of the associated swing bolt, while the furcations 54 and 56 provide bearing surfaces against which tightening nut 33 may be engaged and locked by its associated locking nut. Preferably, member 52, or 52', is in the form of a substantially flat plate having its forward portion inclined or bent downwardly to position notch 53 thereof for receiving the swing bolt.

One of the bifurcated or claw-like members, as 52, and a base plate or block 47 may be arranged in substantially parallel, opposed relation to constitute a pair of upper and lower members embracing the outer end of divergent arms 43, in which position they may be secured in any suitable manner, as by means of bolts 57 and nuts 58. It will also be understood that bifurcated member 52' and a base plate or block 47 may be secured about the outer end of arm 44 in a like manner.

It has been found that by making this bogie coupler of a composite structure of wood and metal, preferably of oak or hickory with steel reinforcing plates and brackets, in accordance with this invention, no universal coupling is required, as the wooden members connecting the front bogie to the Y section act as a torsional member and allow the bogies to twist with respect to each other, as when being removed from the gun emplacement, or traveling over rough terrain. In some instances with this structure under test, it has been noted that the rear bogie was five feet off the road, thereby subjecting the wooden members to severe torsional stresses and yet no failures resulted and the structure withstood these stresses without damage of any kind.

As shown in the drawing, the above mentioned desirable objectives may be attained in accordance with this invention by providing a longitudinal member 42 comprising a wooden section 42', preferably of hickory or oak, substantially co-extensive in length with member 42. The forward end of wooden section 42' may have a metal, preferably steel, reinforcement 61 which, with the exception of the holes for draft pin 22, com-

pletely encases that portion of wooden section 42' which is adapted to extend within recess 24 of the front bogie axle. This reinforcement extends rearwardly preferably completely encasing the top and bottom sides as well as a substantial portion of the adjacent marginal edges of the vertical or lateral sides of wooden section 42', so as to leave a longitudinal opening or slot 62 substantially midway between the top and bottom sides of wooden section 42'. The upper and lower encasing sections of this reinforcement may be secured to wooden section 42' in any suitable manner, as by means of bolts 66.

At the rear end of the coupler, divergent arms 43 and 44 may comprise, respectively, wooden sections 43', 44', likewise preferably of oak or hickory, cooperating with a reinforcement, preferably of steel, comprising upper and lower sections 69 and 71, respectively. As these sections are of like construction and merely oppositely disposed, only upper section 69 is described in detail, and corresponding parts of section 71 are indicated by the same reference characters bearing prime marks. Preferably, upper section 69 is a unitary structure comprising a central, longitudinally disposed portion 72 of downwardly facing channel section from which similar portions 73 and 74, of downwardly facing channel section, branch or diverge, so that central portion 72 may fit over the top side and adjacent marginal edges of wooden section 42', while portions 73 and 74 may be similarly disposed over wooden section 43' and 44'. The upper and lower sections may be secured to wooden section 42', as by a suitable number of bolts 76 through central portions 72 and 72'. In a like manner, these upper and lower sections may be secured to wooden sections 43', 44', as by means of bolts 77 through upper and lower portions 73, 73' and 74, 74' respectively.

In using this coupler with the bogie removed from the mount, the coupler may be and preferably is first connected to the rear bogie by raising maneuvering bar 36 until the upper flat surface 27 of the axle is substantially parallel with the ground and then passing divergent arms 43 and 44 beneath the maneuvering bar and above the axle so that the base blocks have their flat under surfaces 48 resting on upper surface 27 of the axle and on co-planar surfaces 38 of bearing blocks 37, and inclined surfaces 49 and 51 of the base blocks engage inclined surfaces 39 and 29 respectively, of bearing blocks 37 and 28. When this is accomplished, swing bolts 32 may be swung upwardly into notches 53 and secured therein by screwing nuts 33 along these bolts until the tightening nut engages furcations 54 and 56 in which position this nut may be secured by its associated locking nut. It will be seen that in this way the coupler is securely clamped in interlocking engagement with the rear bogie. The front end of the longitudinal member 42 may be pivotally connected to the front bogie axle by inserting the forward end of this member into recess 24 with bore 46 in line with holes 23, and then passing draft or pivot pin 22 through these aligned holes. It will be evident that with the bogie so connected, it may be towed or maneuvered by a vehicle or otherwise as circumstances may require.

It will be understood that in disconnecting the coupler from the bogies the procedure followed is preferably just the reverse of that described above, namely, by removing draft or pivot pin 22 and withdrawing member 42 from the front bogie axle, after which draft pin 22 may be replaced in

the axle, and then by loosening swing bolts 32 and lifting the diverging arms 43, 44 and base blocks 47 off of the rear axle and passing the coupler forwardly beneath the maneuvering bar 36.

From the foregoing, it will be seen that the invention provides a bogie coupler of rugged and dependable construction, which is suitable for towing both bogies simultaneously by the same towing vehicle. This coupler is also capable of being attached to the bogies at the gun emplacement so that they may be towed directly from the emplacement without first being wheeled manually out of this area. This bogie coupler when connected to the bogies makes it possible for a towing vehicle to maneuver the bogie with satisfactory control. This coupler is also adapted for storage in the prime mover and it is capable of being assembled and disassembled from the bogies in very short periods of time.

What I claim is:

1. In a bogie coupling arrangement of the character described for the front and rear bogies of a gun mount, the combination of said rear bogie provided with swing bolts whereby said rear bogie may be secured to said gun mount, a longitudinal member for connection at its forward end to said front bogie, permanently attached arms extending rearwardly from said longitudinal member for connection to the rear bogie, and means carried by said arms for interlocking engagement with said swing bolts.

2. In a bogie coupling arrangement of the character described for the front and rear bogies of a gun mount, the combination of said rear bogie provided with swing bolts whereby said rear bogie may be secured to said gun mount, a longitudinal member for connection at its forward end to said front bogie, permanently attached arms extending rearwardly from said longitudinal member for connection to said rear bogie, a pair of members carried by each of said arms, means providing for interlocking engagement of one of the members of each pair with said rear bogie, and means providing for interlocking engagement of the other of each pair of members with said swing bolts.

3. In a bogie coupling arrangement of the character described for the front and rear bogies of a gun mount, the combination of said rear bogie provided with swing bolts whereby said rear bogie may be secured to said gun mount, a longitudinal member for connection at its forward end to said front bogie, permanently attached arms extending rearwardly from said longitudinal member for connection to said rear bogie, a pair of upper and lower members carried by each of said arms, means providing for substantially

complementary interlocking engagement of the lower member of each pair with said rear bogie and bearing surfaces carried thereby, and means providing for interlocking engagement of the upper member of each pair with said swing bolts.

4. In a bogie coupler for gun mount bogies of the described class including a front bogie axle and a rear bogie axle with mount securable swing bolts carried by the latter, a longitudinal member for connection at its forward end to said front bogie axle, permanently attached arms extending rearwardly from said longitudinal member for connection to said rear bogie axle, and means carried by said arms for interlocking engagement with said swing bolts.
5. In a bogie coupler for gun mount bogies of the described class including a front bogie axle and a rear bogie axle with mount securable swing bolts carried by the latter, a longitudinal member for connection at its forward end to said front bogie axle, permanently attached arms extending rearwardly from said longitudinal member for connection to said rear bogie axle, a pair of members carried by each of said arms, means providing for interlocking engagement of one of the members of each pair with said rear bogie axle, and means providing for interlocking engagement of the other of each pair of members with said swing bolts.
- 20 6. In a bogie coupler for gun mount bogies of the described class including a front bogie axle and a rear bogie axle with mount securable swing bolts carried by the latter, a longitudinal member for connection at its forward end to said front bogie axle, permanently attached arms extending rearwardly from said longitudinal member for connection to said rear bogie axle, a pair of upper and lower members carried by each of said arms, means providing for substantially complementary interlocking engagement of the lower member of each pair with said rear bogie axle and bearing surfaces carried thereby, and means providing for interlocking engagement of the upper member of each pair with said swing bolts.
